UNITED STATES PATENT OFFICE.

ALOIS F. STEIERT AND OSCAR W. LINKE, OF PHILADELPHIA, PENNSYLVANIA, AS
SIGNORS TO S. L. PRODUCTS COMPANY, A CORPORATION OF DELAWARE.

FLOOR POLISHER.

Application filed March 13, 1923. Serial No. 624,819.

Our invention relates to floor polishing devices, and one object of the invention is to provide a polisher which combines with means for applying a polishing medium to the floor or other surface, a container for the medium together with means including a valve for expelling a predetermined amount of the medium from the container.

A further object of the invention is to provide a device of this nature in which the valve mechanism is an extremely simple one.

A still further object of the invention is to provide a device of this nature in which the valve and its operating mechanism are enclosed by the container.

The invention further resides in a novel and advantageous arrangement of elements hereinafter fully described.

With reference to the drawings:

Figure 1, is a longitudinal section through a device made in accordance with our invention;

Fig. 2, is a transverse section on the line 2—2, Fig. 1;

Fig. 3, is a fragmentary perspective illustrating the valve mechanism, and

Fig. 4, is a longitudinal section illustrating a modification of the device.

With reference to the drawings, the device comprises in its preferred form a substantially rectangular casing 1 having a recess 2 in one side, at the bottom of which is an aperture through which the liquid polishing medium may be admitted to the interior of the casing, this aperture normally being closed by a threaded plug 3. The casing also comprises as integral elements a recess 4 at each end which are adapted to hold applicator pads 5, 5, which in one position of the casing bear upon the floor or other surface to which the polish is to be applied and which constitute a means for spreading the polish over the surface and for treating the surface therewith. That side of the container 1 opposite the recess 2 is provided with a flexible formation similar to that employed in oil cans which permits this side to be flexed inwardly to reduce the interior area of the container, a suitable discharge opening being provided through which under such conditions a portion of the contained liquid is ejected. This discharge opening in the present instance is located in the sloping side of a wedge-shaped recess 6 and is controlled by a suitable valve which,

in the present instance, comprises a screw 8 adapted to enter the discharge aperture. The lever arm 9 is pivotally mounted upon a member 10 secured in suitable manner to the inside of the casing 1, and it will be noted that the inclined face of the recess 6 in which the discharge opening is located is provided for strengthening purposes with a washer 7 through which the aperture passes and which is so disposed that the valve bears flat against the inner face thereof, as clearly illustrated in Figs. 1 and 3. The arm 9 projects beyond the pin 11 towards the flexible portion 12 of the casing and normally bears against or lies close to this portion whereby when the latter is flexed inwardly, the contiguous end of the arm is forced inwardly, with the result that the valve 7—8 is elevated from the apertured surface against which it normally bears, thereby opening the discharge aperture and permitting the passage of the contained liquid therethrough.

It will also be noted that simultaneously with the elevation of the valve from the aperture and by reason of the inward flexing of the part 12 of the casing, the interior area of the casing is reduced, with the result that a portion of the liquid contents is actually forced from the casing, the amount of the discharged liquid being controlled by the extent to which the casing is flexed inwardly and the degree to which the valve is opened.

A spring 13 secured to the pin 11 bears against one side of the lever 9 and against the edge of the element 10, this spring tending to retain the valve in the closed position even when the casing is reversed. A rod 14 extends laterally through the casing and projects beyond the sides thereof, the projecting ends of the rod constituting trunnions, by means of which a forked handle 15 may be attached to the casing, the bar 14 also constituting a stop limiting the movement of the arm 9 in the casing. The casing is adapted to receive a hoodlike pad 20 which covers that side of the casing that is flexible and which provides means for further treating and polishing the surface to which the wax or other material has previously been applied.

The operation of the device will be clear from the foregoing description. A quantity of the liquid polish having been placed

in the container, the latter is made to assume the position illustrated in Figs. 1 and 2, in which the applicator pads 5, 5, rest upon the surface which it is desired to polish. A slight pressure by the foot upon the portion 12 of the casing, which is now at the top, causes the valve to open and a portion of the liquid polish to be expelled from the casing onto the surface. The casing is then moved over the surface by means of the handle 15 in such manner as to distribute the liquid and to rub it thoroughly in. When the surface has thus been thoroughly treated with the polish, the casing 1 is swung over to the reverse position in which it rests upon the pad 20, and is again moved over the surface in such manner as by further treatment to give the polished appearance that is desired.

The construction has numerous advantages, the main one being that by employing a positive valve, any tendency of the liquid to leak from the casing is eliminated and the air is kept from circulating through the interior of the casing so that the polish does not deteriorate or harden. By having the discharge opening located in a recess in the casing, there is not the same tendency for the outer surface of the casing to become smeared with the polish, and the construction which provides a pin which actually enters the discharge opening, as does the projecting end of the screw 8, prevents the accumulation of hardened polish around the discharge opening with a possible eventual clogging.

In Fig. 4, we have illustrated a modification in which the valve is eliminated and which, in fact, does not require the provision of the flexible side portion 12, although this may be included if desired. In this instance, one or more comparatively large apertures 16 is provided in the end wall or walls of the container portion of the casing, and the polish reaches the floor surface, by soaking through the pads 17, 17 which may be of felt or like material and which are preferably provided with suitable recesses 18 which register with the apertures 16, as clearly illustrated, whereby the polish may reach the interior of the pad and more readily be passed down to the working surface. By making the apertures 16 comparatively large, it is found that the motion of the casing in operation causes the liquid polish to pass through the apertures into the pad in sufficient quantities to give a proper applica-

tion, and the amount of discharge can be adjusted by varying the size of the aperture or apertures.

We claim:

1. In a floor polishing device, the combination with a container having a discharge opening, applicator elements adapted to support the container in a position permitting ejection of a contained liquid through the discharge opening to the supporting surface, a flexible, wall in said container constituting ejecting means, and a valve normally closing said discharge opening and operatively associated with said flexible wall whereby the opening is uncovered when the flexible wall is pressed inwardly.

2. In a floor polishing device, the combination with a container having a discharge opening, applicator elements adapted to support the container in a position permitting ejection of a contained liquid through the discharge opening to the supporting surface, a flexible wall in said container constituting ejecting means, a valve normally closing said discharge opening, and means operatively associated with the flexible wall for moving the valve inwardly of the container when the flexible wall is pressed.

3. In a floor polishing device, the combination with a container having a discharge opening, applicator elements adapted to support the container in a position permitting ejection of a contained liquid through the discharge opening to the supporting surface, a flexible wall in said container constituting ejecting means, and a valve adapted to close said discharge opening, a lever pivotally secured within the container and connected at one end with the valve, the other end of the lever lying contiguous to the flexible wall whereby movement inwardly of the latter may open the valve.

4. In a floor polishing device, the combination with a container having a discharge opening in one side and on the opposite side a flexible wall constituting means for ejecting a contained liquid from said opening, applicator elements adapted to support the container in a position permitting ejection of said contained liquid through the discharge opening to the supporting surface, a valve adapted to close said discharge opening, and means operatively connecting the valve with said flexible wall whereby when the latter is pressed inwardly the opening is uncovered.
